UNITED STATES PATENT OFFICE.

ARTHUR R. McCREARY, OF KANSAS CITY, MISSOURI.

ADVERTISING DEVICE.

Specification of Letters Patent.

Patented June 25, 1918.

Application filed April 5, 1917. Serial No. 159,990.

To all whom it may concern:

Be it known that I, ARTHUR R. McCREARY, a citizen of the United States, residing at Kansas City, in the county of Jackson and State of Missouri, have invented certain new and useful Improvements in Advertising Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to advertising devices and has for its principal object to provide mechanism for successively bringing letters into display position to form words or sentences whereby public attention will be attracted.

It is also an object of the invention to provide an endless link belt, wherein each link consists of a carrying member for a letter or symbol, and to provide guide members whereby the belt may be successfully carried in an inclined position if desired.

A further object of the invention is to provide improved means for pivotally connecting the belt links, for driving the belt and for illuminating the characters displayed.

In accomplishing these objects, I have provided improved details of structure the preferred forms of which are illustrated in the accompanying drawings, wherein:

Fig. I is a perspective view of an advertising device constructed according to the present invention, a part being broken away for better illustration.

Fig. II is a transverse vertical section on the line II-II, Fig. IV.

Fig. III is a transverse vertical section taken on the line III-III, Fig. IV.

Fig. IV is a longitudinal vertical section particularly illustrating the location of the driving motor and belt illuminating lamps.

Fig. V is a horizontal sectional view illustrating the connection of the belt links and the mounting of the character plates.

Fig. VI is a detail perspective view of a portion of the link belt showing the insertion of a double width link.

Referring more in detail to the drawings:

1 designates a housing which is preferably

of sheet metal construction, is rectangular in vertical cross section and may be made of various lengths, and is provided with a front side opening 2 containing a transparent panel 3 along which the display is moved and through which it may be observed. The housing is also provided with a hinged covering 4 which may be opened to permit insertion or removal of the characters from the belt links or carriers and is provided with perforations 5, for permitting a circulation of air through the housing to prevent excessive heating by the lamps placed within the housing for illuminating the belt characters.

Located within the housing at its opposite ends are shaft carriers 6, comprising upper and lower horizontal plates 7-7' spaced by vertical connecting standards 8 at their opposite sides, and revolvably mounted in each of said carrier plates 7-7' is a vertical shaft 9, whereon upper and lower spaced drums 10 and 11 are fixed and which carry an endless link belt 12; the lower drums being provided with extended peripheral base flanges 13 for preventing the belt, during its travel, from being displaced from the drums.

To guide and support the belt as it travels between the carrying drums, I provide channel or trough members 14-14', which extend between and are mounted at their opposite ends on the carrier plates 7' to slidably receive the lower edges of the belt and the upper edges of the belt are retained in alignment by the downturned flanges 15 of angle bars 16-16' that extend between the carriers and are adjustably attached to the plates 7 and serve, not only as guide members for the belt strands, but also afford means for holding the end carriers at a definite spaced relation to maintain a certain tension on the belt.

To actuate the belt about the drums, I provide one of the end shafts 9 with a driving gear wheel 18, which is fixed to the shaft and travels in mesh with a smaller gear wheel 19, keyed on a stub shaft 20 that is revolvably carried in the carrier plate 7. Fixed on the shaft 20 and overlying the gear wheel 19, is a larger gear wheel 21 which travels in mesh with a gear wheel 22 revolvably mounted on the upper end of the shaft 9 and fixed to the under face of a pulley wheel 23. Mounted centrally within

the housing is an electric motor 25 having a drive shaft 26 provided with a pulley wheel 27 and running thereon and on the pulley wheel 23, is a belt 28, whereby actuation of the motor, through the reducing gears, will revolve the shaft 9 and belt drums to move the belt within the housing so that the characters mounted thereon will successively be brought in display position adjacent the panel 3.

The belt 12, in its preferred construction, comprises a plurality of metal link panels 30 of rectangular form, comprising vertical side rails 31 and horizontal end rails 32; 15 the vertical rails being provided at their outer edges with inturned flanges 33 and the base rails with upturned flanges 34 forming channels wherein transparent character plates 35 may be slidably located, and the 20 links are connected to form a continuous belt by means of intermediate strips 36 having inturned flanges 37 along their vertical edges forming channels for receiving the inner edges of the vertical panel rails 31 between the end rails 32 to provide a pivotal connection between the links.

The strips 36 have an outstanding back rail 38, which is adapted to seat against the carrying drums 10—11 so that as the belt 30 travels therearound the character plates 35, which are preferably of glass, will be held from the drum periphery to prevent end pressure thereagainst and cracking of the plates.

35 The character plates 35, are each removable from the belt links and may contain letters which may be arranged on the belt to form words and sentences; the body of the plate being covered with an opaque material while the character is transparent.

To illuminate the characters, I provide a number of lamps 40 which are located between the belt strands along a plate 42 spaced from the main base of the housing 45 and which are connected through a switch (not shown), with an electric circuit by circuit wires 43 extended to the lamps between the housing floor members.

In order that pictures, etc., may be displayed by the belt which are wider than the usual links, I provide special hinged connected links 45, Fig. VI, wherein the horizontal rails at the hinged edges are removed so that a picture or card may be 55 held by the outer rails of two connected links.

Assuming that the parts are so constructed, in using the device the character plates are arranged in the belt links to form words 60 and sentences which are successively brought into and from displaying position before the

panel 3 by operation of the belt driving motor.

It is also apparent that advertising cards, pictures or other articles may similarly be 65 displayed and that with the belt guide mechanism provided the belt may be operated in an inclined, horizontal or vertical position with equal success.

It is also apparent that the lighting means 70 provided will enable the sign to be read or seen at night and will further attract attention to the display.

It will be seen also that should a belt link break or become disconnected, it may be 75 quickly and easily removed and replaced by a similar link and that the operation of the device may be resumed without the insertion of an entirely new belt as is the case where continuous belt bands are used.

Having thus described my invention, what I claim as new therein, and desire to secure by Letters-Patent, is:

1. In a device of the character described comprising spaced drums, a belt operating 85 over said drums and comprising a plurality of links; said links comprising opposite side and end rails, and connecting plates having back-turned edges forming facing pockets for pivotally receiving the inner edges 90 of the side rails of adjacent links to connect the latter for the purpose set forth.

2. In a device of the character described comprising spaced drums, a belt operating 95 over said drums and comprising a plurality of links; said links comprising opposite side and end rails having inturned edges forming a pocket for receiving a panel, and connecting plates having back-turned longitudinal edges forming pockets for pivotally 100 receiving the inner edges of the side rails of adjacent links to pivotally connect the latter.

3. In a device of the character described comprising spaced drums, a belt operating 105 over said drums and comprising a plurality of links, said links comprising opposite side and end connecting rails forming an open frame, said side rails and lower end rail having their outer edges turned outwardly 110 to form a pocket for receiving a panel, connecting members for said links comprising plates having their longitudinal edges turned outwardly, then inwardly, to form facing pockets for pivotally receiving the 115 inner edges of the side rails of adjacent links, and having a longitudinal rail adapted for contacting the face of said drums to space the links therefrom for the purpose set forth.

In testimony whereof I affix my signature.
ARTHUR R. McCREARY.
